Porthole Closure Latch

Filed July 16, 1929

UNITED STATES PATENT OFFICE

DAVID G. EARL, OF LONG BEACH, CALIFORNIA

PORTHOLE CLOSURE LATCH

Application filed July 16, 1929. Serial No. 378,645.

This invention relates to a port hole closure lock particularly useful in banks, armored cars or similar places where it is necessary to protect men against bandits, 5 robbers or other lawless people.

An object of my invention is to provide a closure for a port hole which can not be opened from the outside.

A further object is to provide a closure of 10 the character stated which can be quickly and easily opened from the inside by the barrel of the pistol or similar weapon.

Still a further object is to provide a closure of the character stated which is simple 15 in construction, is easily operated and will not readily get out of order.

Other objects, advantages and features of 20 invention may appear from the accompanying drawings, the subjoined detailed description and the appended claims.

In the drawings:

Figure 1 is a front elevation of my port hole closure in closed position.

Figure 2 is a front elevation of the same 25 in open position.

Figure 3 is a sectional view taken on line 3—3 of Figure 1.

Figure 4 is a fragmentary, sectional view taken on line 4—4 of Figure 1.

Referring more particularly to the drawings, the wall 1 which may be that of a bank, 30 armored car or the like, is provided with a port hole 2. My closure comprises a plate 3 which is bolted, welded or otherwise suitably secured to the wall 1. The plate 3 extends 35 over the port hole 2 and is provided with a hole 4 which co-incides with the port hole 2. A pair of vertical guide strips 5—6 are provided on the plate 3 and are preferably integral therewith.

A shutter plate 7 is slidably mounted in 40 the guide strips 5—6 and is adapted to be moved vertically so as to open and close the holes 2—4. When the plate 7 is in its lowermost position, it rests upon stop pins 8—8 which limit its further downward movement. When the plate is in its lowermost position it is locked by means of the latch arm 9 which is pivotally mounted to the plate 3 as 45 at 10. A slot 11 is cut through the guide

strip 5 and the latch arm 9 is provided with a head 12 which extends through the slot 11 and over the upper edge of the plate 7 so as to hold said plate against accidental upward movement.

The arm 9 normally hangs as shown in Figure 1, due to the action of gravity, and the plate 7 is consequently locked. If it is desired to shoot through the holes 2—4, the operator places the muzzle of the weapon to one side of the arm 9 and then moves the muzzle to the right and upwardly, thus swinging the arm to one side and at the same time moves the plate 7 upwardly to expose the holes. This can all be done with one 60 movement, and is quickly and easily accomplished. When the muzzle of the gun is removed from the holes 2—4, the plate 7 and the arm 9 drop down by gravity and the plate is locked.

Having described my invention, I claim:

1. A port hole closure latch comprising a plate, means securing said plate over the port hole, a shutter plate slidably mounted in the first named plate, and over the port hole, 75 an arm pivotally mounted in the first named plate and normally hanging vertically and a head on said arm adapted to engage the top of the shutter plate when said shutter plate is in position to close the port hole, said 80 shutter plate and arm being urged to closed position by their weight.

2. A port hole closure latch comprising a plate, means securing said plate over the port hole, guide strips in said plate, a shutter plate slidably mounted in said guide strips and adapted to open or close the port hole, a latch arm pivotally mounted on one of said strips, said strips having a slot formed therein, and a head on said arm adapted to extend 85 through said slot and over said shutter plate when the shutter plate is in lowered position over the port hole.

In testimony whereof I affix my signature.

DAVID G. EARL. 95
